UNITED STATES PATENT OFFICE

BERTA L. KELLEY AND LOUISE WINNIFORD, OF SANTA BARBARA, CALIFORNIA

DESIGN FOR DOLL

Application filed February 21, 1931. Serial No. 38,789. Term of patent 3½ years.

To all whom it may concern:

Be it known that we, BERTA L. KELLEY, and LOUISE WINNIFORD, citizens of the United States, residing at Santa Barbara, in the county of Santa Barbara, and State of California, have invented a new, original, and ornamental Design for a Doll, of which the following is a specification, reference being had to the accompanying drawings, forming part thereof.

We claim:

The ornamental design for a doll as shown.

BERTA L. KELLEY.
LOUISE WINNIFORD.
